5 Claims. (Cl. 82—25)

The present invention has for an object provision of an automatic lathe comprising at least two radial tool-holders sliding in guides carried by the front face of the headstock and the radial movements of which are controlled by a cam-shaft through the agency of transmission members including two feelers cooperating with the profile of at least one cam, characterized by the fact that these transmission members further include a single chain of mechanical members connecting the said two feelers to a single actuating member controlling positively (drivingly) the movements of the said radial tool-holders in their forward movement and sensitively (resiliently) in their backward movement.

The accompanying drawing shows diagrammatically and by way of example one embodiment of the present invention.

FIG. 1 is an end view of the lathe, certain parts being seen in section showing the control of the radial tool-holders object of the invention.

FIG. 2 is a section along line II—II of FIG. 1.

FIG. 3 is a section along line III—III of FIG. 1.

Referring to the drawing the automatic lathe comprises a frame 1, a spindle 2 pivoting in a headstock 3 fixed on the frame of the lathe and two radial tool-holders 4, 5 sliding in guides (not shown) carried by the front face of the headstock 3. The radial movements of these tool-holders are controlled by a cam-shaft 6, driven to rotate in known manner by a motor (not shown), through the agency of transmission members including at least one cam carried by the cam-shaft 6 cooperating with two feelers and a single chain of mechanical members connecting the said two feelers to an actuating member controlling the movements of the said radial tool-holders 4, 5 positively (drivingly) during their forward movement and sensitively (resiliently) during their backward movement.

In the embodiment shown in the drawing the cam-shaft 6 carries two cams 7, 8 angularly offset one with respect to the other and each cooperating with a feeler 9, 10 both rigidly connected by arms 11, 12 to a toothed sector 13 pivoting on a shaft 14 rigidly secured to a lug 15 of the frame 1. These feelers 9, 10 are each in contact with one of the cams 7, 8 thus determining the angular position of the toothed sector 13 dependent on the angular position of the cam-shaft 6. The toothed sector 13 meshes with a rack 16 carried by one of the ends of a connecting bar 17 disposed vertically and extending across the headstock 3. This connecting bar 17 slides inside the headstock 3 but its angular position relative to this headstock is fixed. The upper end of this connecting bar carries a rack 18 in mesh with a toothed sector 19 integral with a shaft 20 pivoting on the headstock 3. This connecting bar 17 thus drives the toothed sector 19 through angular movements depending on those of the toothed sector 13, these angular movements are therefore dependent on the rotation of the cam-shaft 6.

This toothed sector 19 drives, in its angular oscillations, an actuating member 21 also rigidly fixed to the shaft 20. This actuating member comprises two thrust members 22, 23 disposed symmetrically on either side of the shaft 20. Each of these thrust members 22, 23 is situated on the path of the upper end 24, 25 of a rack 26, 27 sliding freely in the headstock 3. The teeth of these racks

2

26, 27 mesh with a corresponding pinion 28, 29 pivoting on the headstock 3 and in gear with toothings 30, 31 carried by the corresponding radial tool-holder 4, 5.

The radial tool-holders 4, 5 are each subjected to a resilient return action, constituted by a spring 32, 33 in the example shown, tending to retain these tool-holders in their return travel end stroke position. This return travel end stroke position is determined by means of an adjustable abutment 34, 35 rigidly fixed to the headstock 3.

10 In the figure of the drawing the two radial tool-holders 4, 5 are held in the return travel end stroke position by means of the springs 32, 33 so that the racks 26, 27 are held in their high position and the upper ends 24, 25 of each of them is in contact with the corresponding thrust member 22, 23 of the actuating member 21 which is in a neutral or horizontal rest position.

The operation of the control device for the radial tool-holders described is the following:

Each of the cams 7, 8 is constantly in contact with 20 the corresponding feeler 9, 10 so that the toothed sector 13 is maintained positively, in the two directions, in an angular position determined by the angular position of the cam-shaft 6.

When, from the neutral or rest position shown, the 25 toothed sector 13 moves angularly in the direction of the arrow f for example, as a result of a rotation of the cam-shaft 6, this toothed sector drives, through the agency of the connecting bar 17, the toothed sector 19, through an angular movement in the same direction.

30 The angular movement of the toothed sector 19 causes, through the agency of the shaft 20, a similar angular movement of the actuating member 21.

The pivoting of the actuating member 21 in the direction of the arrow g brings about the downward movement 35 of the rack 27 through the agency of the thrust member 23 which causes the pinion 29 to rotate driving in its turn the tooth 31 carried by the tool-holder 5 in the direction of the arrow h. The tool-holder 5 is thus moved towards the work-piece in a forward travel against the action of

40 its return spring 33.

This tool-holder 5 is thus actuated positively in its forward movement by an amount determined by the shape of the cams 7, 8 carried by the cam-shaft 6 and corresponding to the machining operation to be effected.

45 Then, once the forward travel end stroke position of the tool-holder 5 has been reached, the angular movement of the sector 13, driven by the cams 7, 8 cooperating with the feelers 9, 10 changes direction and moves in the reverse direction of the arrow f which brings about, 50 always through the agency of the connecting bar 17, of the toothed sector 19 and of the shaft 20, an angular movement of the actuating member 21 in a direction the reverse of that of the arrow g.

55 As from this moment, the backward travel of the tool-holder 5 is started and the same is controlled sensitively, the rack 27 being applied against the thrust member 23 of the actuating member 21 through the action of the return spring 33, until the said tool-holder 5 reaches the end of its backward travel at which it rests on its adjustable abutment 35 and at which the actuating member 21 is in the neutral or horizontal rest position.

60 During all this time, forward and backward travel of the tool-holder 5, the tool-holder 4 remains in its backward travel end stroke position, held against its adjustable abutment 34 through the action of the return spring 32. Indeed, during the angular movement of the actuating member 21 in the direction of the arrow g from its neutral rest position, the thrust member 22 leaves the front face of the end 24 of the rack 26, the high position of the latter being determined by the adjustable abutment 34.

65 Then, when the actuating member 21, driven by the

cams 7, 8, continues to move in the reverse direction to that of the arrow *g* but oversteps its neutral rest position, the thrust member 22 actuates the rack 26 in a downward direction and thus causes, through the agency of the pinion 28 and of the toothed gear 30, the forward travel of the tool-holder 4 against the action of its return spring 32. Finally, when the tool-holder 4 has reached its forward travel end stroke position, determined by the cams 7, 8, the angular movement of the sector 13 and therefore of the actuating member changes direction and the tool-holder effects its backward travel under the action of its return spring tending to push the upper part 24 of the rack 26 against the thrust member 22. Finally, when the tool-holder 4 reaches the end of its backward travel, determined by its adjustable abutment 34, the actuating member 21 is again in its neutral rest position.

Here again, as for the tool-holder 5, the tool-holder 4 is actuated in its forward travel and sensitively in its backward travel.

In the example shown, the adjustable abutments 34, 35 determining the backward travel end stroke position of the tool-holders 4, 5 are adjusted so that these two radial tool-holders are never simultaneously in motion. Indeed, when one of them moves, the other is maintained at rest against its backward travel end stroke abutment. However, for other adjustments of these end stroke abutments, for example when the backward travel end stroke position of the tool-holder does not correspond to the neutral rest position of the actuating member 21, it is possible that during a part of the cycle of the movement of one of the tool-holders, the other tool-holder is also in motion.

In any case, this control device for the radial tool-holders of an automatic lathe permits of reducing, practically by half, the travels of the said radial tool-holders relative to existing devices in which the said tool-holders are constantly simultaneously in motion in opposite directions one with respect to the other.

This reduction of the travel of the radial tool-holders 4, 5 attributes to the automatic lathe according to the invention appreciable advantages of which the principal ones are:

(a) Reduction of the bulkiness of the lathe which is very important.

(b) As a result, it is no longer possible to uncover, during the backward travel of the tool-holders, the slides of these tool-holders so that these slides are no longer exposed to shavings or other fragments which may give rise to jamming of the tool-holders or a very pronounced wear of these slides.

I claim:

1. An automatic lathe comprising at least two radial tool-holders sliding in guides carried by the front face of the headstock and the radial movements of which are controlled by a cam-shaft through the agency of transmission members including two feelers cooperating with the profile of at least one cam, in which these transmission members further include a single chain of mechanical members connecting the said feelers to a single actuating member which is movable angularly about an axle perpendicular to the front faces of the headstock and comprises two thrust members disposed symmetrically on either side of the said axle, said actuating member drivingly controlling the movements of the radial tool-holders during their forward movement and resiliently during their backward movement.

2. An automatic lathe comprising at least two radial tool-holders sliding in guides carried by the front face of the headstock and the radial movements of which are controlled by a cam-shaft through the agency of transmission members including two feelers cooperating with the profile of at least one cam, in which these transmis-

sion members further include a single chain of mechanical members connecting the said feelers to a single actuating member which is movable angularly about an axle perpendicular to the front faces of the headstock and comprises two thrust members disposed symmetrically on either side of the said axle and located on the path of a rack meshing with a pinion in gear with a toothed gear carried by the corresponding tool-holder, said actuating member drivingly controlling the movements of the radial tool-holders during their forward movement and resiliently during their backward movement.

3. An automatic lathe comprising at least two radial tool-holders each of which is subjected to a flexible return action tending to maintain it in its backward end stroke position determined by an adjustable abutment fixed on the headstock, said tool-holders sliding in guides carried by the front face of the headstock and the radial movements of which are controlled by a cam-shaft through the agency of transmission members including two feelers cooperating with the profile of at least one cam, in which these transmission members further include a single chain of mechanical members connecting the said feelers to a single actuating member which is movable angularly about an axle perpendicular to the front faces of the headstock and comprises two thrust members disposed symmetrically on either side of the said axle, said actuating member drivingly controlling the movements of the radial tool-holders during their forward movement and resiliently during their backward movement.

4. An automatic lathe comprising at least two radial tool-holders sliding in guides carried by the front face of the headstock and the radial movements of which are controlled by a cam-shaft through the agency of transmission members including two feelers cooperating with the profile of at least one cam, in which these transmission members further include a single chain of mechanical members connecting the said feelers to a single actuating member which is movable angularly about an axle perpendicular to the front faces of the headstock and comprises two thrust members disposed symmetrically on either side of the said axle and located on the path of a rack meshing with a pinion in gear with a toothed gear carried by the corresponding tool-holder, said thrust members and rack being constructed and arranged so that during movement of one of the tool-holders only one of the thrust members is in contact with its corresponding rack, said actuating member drivingly controlling the movements of the radial tool-holders during their forward movement and resiliently during their backward movement.

5. An automatic lathe comprising a headstock, guides carried by the headstock, first and second radial tool-holders slideable in said guides, a single angularly moveable actuating member for actuating both said radial tool-holders, a cam-shaft, feelers cooperating with the cam-shaft profile, a single chain of mechanical members connecting said feelers and said angularly movable actuating member to positively control movement of one of said radial tool-holders towards a workpiece, and resilient means controlling the reverse movement of the other of said tool-holders while said one of said tool-holders moves towards the workpiece.
